SUSPENSION LINE FOR PARACHUTES AND
THE LIKE

Leonard P. Frieder, New York, N. Y.

Application October 24, 1938, Serial No. 236,809

6 Claims. (Cl. 96—25)

This invention relates generally to parachutes and has particular reference to the manufacture of suspension cords or shroud lines for use in suspending the load from the sail.

One object of the invention is to provide a cord of the kind indicated, which is very strong as compared with prior cords of the same cross section and which is at the same time so constructed that it will yield to absorb shock when the parachute opens. The construction is such that the cord may be used to suspend the load from the outer ends of the seams connecting together the gores of a parachute sail or it may be extended along such seams and be so adjusted as to yieldingly reinforce the seams.

More specifically the invention includes a novel way or method of making parachute suspension cords or shroud lines as well as the article resulting from the method.

With the foregoing and other objects in view the invention consists in a novel construction and relation of the components of the article, as well as a novel way of constructing and assembling the components. The invention is hereinafter explained with reference to the drawing which accompanies and forms a part of this specification, the novel features being pointed out in claims appended hereto.

The accompanying drawing shows, on a scale which is not necessarily the exact one, how the different components of the cord are first constructed and then assembled into the finished article.

The illustrative embodiment in the drawing is that of a coreless braided silk cord or rope. The first step in the manufacture consists in bringing together a number of natural silk fibers into strands 10 of any desired length. The fibers of silk are parallel in each of the strands and it is preferred to give them a slight twist so that the fibers in a strand may be kept together and thereby made easier to handle as units in the various steps of manufacture. The twist illustrated at 11 in the drawing is somewhat exaggerated for the sake of clarity, the twist being sufficient only for the purpose indicated and performs no function in the load sustaining operation of the strand in the completed article. For this reason the term "substantially untwisted" is used in describing the strands in the specification and in some of the claims, the purpose being to thereby distinguish from a construction in which the strands are twisted enough to give the twist a functional purpose in the load sustaining operation of the cord.

The fibers or filaments of natural silk have some twist or crimp which adds to the resiliency of the completed cord, but care should be taken to get substantially the same tension in all of them. When more exact uniformity of tension is advisable the silk fibers may be stretched under water and then dried, the stretch varying according to the amount of twist or crimp but never exceeding the elastic limits of the fibers.

5

10 This stretching and drying may be performed before the fibers are given the slight twist to form the strands 10, but it has been found to be more convenient and just as satisfactory to do the stretching and drying after the slight twist 15 has been given to the strand.

This stretching and drying brings all the fibers under substantially equal tension and the strands have no rough surfaces or loops of single fibers projecting from the strands.

20 In the embodiment shown in the drawing eight of the strands above described are brought together in parallel relation to form what is usually referred to herein as a tape 12. Eight of these groups or tapes are employed in weaving or braiding the finished article illustrated. This braiding may be done on a braiding machine which is constructed to hold the strands in the flat or tape relation while performing the braiding operation, but is otherwise a more or less standard machine.

25 The braiding is an over and under braiding in which the tapes extend in oppositely running spirals as shown, and care is taken to see that the tension is so adjusted that the finished article is a soft loose braid although, of course, this may 30 be varied according to special requirements. The finished article has no core of material running lengthwise through its center so the finished article may be visualized as operating somewhat in the nature of a spring which will yield and 35 recover when load is applied and removed.

Owing to the fact that the strands 10 are un-twisted or substantially so, the exposed fibers of the strands will lie substantially parallel on exterior of the finished cord and at angles approaching nearer parallelism with the axis of the cord than if the strands had a relatively high twist. As a result, the fibers or filaments on the exterior will cause the finished cord or rope to have a very smooth surface which will not catch 45 and fray when dragged over rough surfaces, or burn under friction, or pick up dirt. It will be much stronger for the same cross-section than any cord now available for use in connection with parachutes. In addition, it may, on account of 50 the method of construction, be adjusted by push-

ing endwise to loosen the braid slightly and the cord then flattened slightly when it is desired to have a part of a shroud line in or along the seam connecting the gores of a parachute, thereby co-ordinating the extensibility of the cord with the extensibility of the seam, while, at the same time, providing a very strong reinforcement when the limit of that extensibility is reached.

One advantage of the construction is that on account of its great strength and other characteristics stated it is possible to use a larger number of suspension cords or shroud lines for a sail without greatly increasing the bulk of the parachute as a whole. This, in turn, makes it possible to use relatively long and narrow gores, and more of them than has heretofore been possible in making a sail, thereby not only increasing the reinforcement afforded by the more numerous seams connecting the gores, but also effecting a better distribution of the load over the sail area. Also, owing to the construction, the lines are capable of being folded into any sort of a pack or container without danger of weakening at places where sharp folds or bends might occur and, on account of the smooth exterior surface, there will be no harmful friction between the cords or between the cords and the sail of the parachute when the parachute is put into use.

While silk is preferred and has so far been the only material referred to, rayon filaments may be used instead of silk and in substantially the same way. Also, instead of either silk or rayon, cotton may be employed, although it has disadvantages as compared with either silk or rayon. When cotton is used, each of the strands 10 is made up of a plurality of fine threads, each twisted sufficiently to give the maximum strength, brought into parallelism to form the strand, and the strand then given the same sort of low twist as is above described in connection with the silk construction. In other words, fine highly twisted cotton threads are substituted for the silk or rayon filaments, but the procedure is otherwise substantially the same in making the article. Owing to the high twist given to the cotton filaments or threads, the exterior of the finished cotton cord or rope will have a smooth exterior like that of the silk article.

While the novel cord or rope has been described in detail, and also the method of making it, it will be apparent to those skilled in the art that changes may be made in the article and

method of producing it which will yield substantially the same results, all of which changes come within the scope of the claims which follow.

5. What is claimed is:

1. A method of making shroud lines for parachutes and the like which comprises the grouping together of parallel silk filaments to form a plurality of strands, stretching the strands under water and drying them, dividing the plurality of strands into groups and bringing the strands into parallel relation to constitute a plurality of tapes, and then braiding the plurality of tapes together to construct the finished line.

15 2. A method of making suspension cords for parachutes and the like which comprises bringing together of a plurality of parallel silk filaments to form a strand, stretching the strand under water and drying it, bringing a plurality of strands into parallel relation to form a plurality of tapes, and braiding the tapes together to construct a substantially round line.

25 3. A method of making suspension cords for parachutes and the like which comprises constructing strands from substantially untwisted parallel silk filaments, forming a plurality of flat twistless tapes by bringing a plurality of strands into parallel relation to form each tape, and then braiding said tapes together while flat to complete the cord.

30 4. A suspension cord for parachutes and the like consisting of a plurality of groups of strands braided together, each of said strands consisting of a plurality of permanently stretched silk filaments in parallel relation.

35 5. A suspension cord for parachutes and the like consisting of a plurality of flat tapes loosely braided together while flat, each of said tapes being composed of a plurality of parallel strands, and each of the strands being composed of a plurality of parallel permanently stretched silk filaments with the filaments in each strand in substantially untwisted condition.

40 6. A method of making suspension cords for parachutes and the like which comprises constructing substantially untwisted strands from parallel filaments, constructing a plurality of flat twistless tapes each composed of a plurality of said strands in parallel relation, and then 45 braiding said tapes together while flat to form a substantially round cord.

LEONARD P. FRIEDER.
